CHILD'S SANDAL OR SIMILAR ARTICLE

George Codish, New York, N. Y.

Application June 18, 1949, Serial No. 3,393

Term of patent 3½ years

(Cl. D7—7)

To all whom it may concern:

Be it known that I, George Codish, a citizen of United States, residing at New York city, in the county of Bronx and State of New York, have invented a new, original, and ornamental Design for a Child's Sandal or Similar Article, of which the following is a specification, reference being had to the accompanying drawing, forming part thereof.

In the drawing:

Fig. 1 is a top plan view of a child's sandal showing my new design;

Fig. 2 is a side elevational view thereof.

I claim:

The ornamental design for a child's sandal or similar article, as shown.

GEORGE CODISH.
